UNITED STATES PATENT OFFICE.

ARTHUR WILLIAMS, OF GRAND RAPIDS, MICHIGAN, ASSIGNOR TO WILMARSH & MORMAN COMPANY, OF GRAND RAPIDS, MICHIGAN, A CORPORATION OF MICHIGAN.

DRILL-HOLDER.

1,391,034.

Specification of Letters Patent. Patented Sept. 20, 1921.

Application filed September 7, 1920. Serial No. 408,496.

To all whom it may concern:

Be it known that I, ARTHUR WILLIAMS, a citizen of the United States of America, residing at Grand Rapids, in the county of Kent and State of Michigan, have invented certain new and useful Improvements in Drill-Holders; and I do hereby declare the following to be a full, clear, and exact description of the invention, such as will enable others skilled in the art to which it appertains to make and use the same.

This invention relates to drill holders. In grinding drills for use in drilling metal, it is important that the drills be held in proper relation to the grinding wheel to obtain the proper angle of grind, particularly when the grinding is done with more or less unskilled labor. It is a primary object and purpose of the present invention to make a drill holder which is capable of handling all diameters of drills between the largest and smallest drills which the holder is adapted to receive and to hold any of such drills in proper position with reference to the grinding wheel that a true and accurate grinding of the drill may be had, the proper angles to the cutting lips being obtained together with sufficient lip clearance and the right angle of the dead center line. A further object of the invention is to make a supporting shank or end support for the drills which is adjustable in a novel manner for the different diameters of drills, making use of a plurality of supporting centers whereby the amount of adjustment in any case will not be more than one-half of an inch with the distance between centers equal to one and five sixteenths inches, though, of course, the number of centers and the distances between is not restricted in any sense, being a matter of desired design. Various other objects and purposes than those specifically stated will appear as understanding of the invention is had from the following description, taken in connection with the accompanying drawing, in which,

Figure 1 is a side elevation of the drill holder, showing its application to a grinding machine, the upper part of which appears in the figure.

Fig. 2 is an enlarged side elevation of the shank support for drills in the drill holder, parts being broken away and shown in sec-

tion to more clearly disclose the construction.

55

Fig. 3 is an end elevation of the construction shown in Fig. 2, and,

Fig. 4 is a section on line 4 of Fig. 1.

Like reference characters refer to like parts in the different figures of the drawing.

60

The drill holder includes in its construction an elongated bar 1 which, at one end, is formed with two upwardly extending angularly positioned sides 2 adapted to make a rest for the drill at the cutting end thereof, 65 said sides 2 being made integral with the bar 1 and being cut at one edge to correspond with the face of the grinding wheel 4 when the holder is attached to a grinding machine, said edges 3 of the sides 2 being vertical 70 when thus positioned and paralleling the face of the grinding wheel. The grinding wheel is secured at one end of a shaft 5 rotatably mounted at the upper end of a column or similar support 6. Shaft 5 is adapted to be driven by a belt passing around a pulley 7 on the shaft. Any other equivalent means of driving may be used. A bracket 8 is attached to the bar 1 near its upper end and is swivelly mounted in a socket 9 formed 80 on a bracket 10 which, in turn is rotatably mounted on a stud shaft 11 projecting from the column 6. The angle of the swivel mount of bracket 8 together with the adjustable connection of bracket 10 on the 85 shaft 11 permits any desired range of adjustment of the drill holder to the grinding wheel and in practice, said drill holder extends downwardly at an angle to the vertical from its upper end as shown.

90

The support for the end of the shank of the drill comprises a bracket 12 having a foot piece 13 adapted to slide on the upper side of bar 1 and from which a rod 14 threaded at its lower end extends downwardly through said bar 1 which is slotted for the passage of the rod. A clamping nut 15 threads on to the end of rod 14 and binds against the under side of bar 1 to secure said shank support against movement. 100 Bracket 12 at its upper part is formed with an enlarged portion 16. A rod 17 passes therethrough and is adjustable lengthwise thereon, being keyed against rotation as shown. An adjusting screw 18 passes into 105 the portion 16 below rod 17 and threads

through a nut 19 set into said portion 16, being formed adjacent its outer end with a narrow collar 20 which is received in an annular groove 21 made in rod 17 near its 5 outer end. The screw 18 is equipped with an operating head 22 for manual operation, it being evident from this construction that by turning the head, rod 17 and attached parts may be moved any desired amount in 10 either direction with respect to the supporting bracket 12.

At its inner end the rod 17 is enlarged as indicated at 23, and has a guide block 24 attached thereto in the face of which a dove-tail groove is cut vertically to receive a slide 25, the same being slidably mounted between vertical guides 24^a, one at each side of the guide block. A plurality of centers 26 extend from the slide 25, being located equal 20 distances apart. In the rear side and near the upper end of the slide 25 a groove 27 is cut in which a collar 28 on an adjusting screw 29 is located, the screw threading into the block 24 and having an operating head 30 at its upper end for manual operation. The raising or lowering of the slide 25 is accomplished by turning screw 29 as is obvious.

On one of the guides 24^a, a scale as indicated at 31 is made having a center line marked 0 and graduated marks in fractions of an inch both above and below the center line for one half of an inch. On the slide 25 a line, indicated at 32, is made. The centers 26 are indicated as 1, 2 and 3 and when the line 32 is in conjunction with the center line at 0 on scale 31, the different centers are properly positioned to take one inch, two inch and three inch drills. It is obvious 40 that movement of the slide in either direction will position the centers to take either larger or smaller drills than those indicated by their numerals, depending upon the direction of movement of the slide, and that 45 any diameter of drill between may be held in the drill holder as well as the three sizes named by proper adjustment of the slide with respect to the scale.

Drills are held in the front support furnished by the angularly positioned sides 2 and securely held at their shank ends on the centers 26 as shown in Fig. 1 where the drill 50 33 is thus supported. This drill holder is relatively simple in construction, furnishes 55 a perfect support for the drill of whatever size and holds it in proper position for grinding, grinding the lips of the drill equally and with the same angle to the axis of the drill, both lips being given the same clearance angle and with the angle of the dead center line ground properly. With this drill 60 holder the necessity of an intermediate support for the body of the drill is obviated. The construction is very practical, and long 65 ranges of adjustment for different sizes of

drills are obviated with the plurality of centers used.

The invention is defined in the appended claims and I consider that the invention comprehends all forms or modifications in 70 structure that come within the scope of the said claims.

I claim:

1. A drill holder comprising an elongated supporting bar formed at one end with an angularly disposed sides making a V-shaped trough to receive the end of the drill to be ground, a bracket slidably mounted on the bar adjacent the other end thereof, a rod passing through the bracket above the bar, 75 means to adjust said rod lengthwise to different positions, a guide block on the inner end of the rod, a slide adjustably mounted on the guide block and adjustable vertically with respect thereto, means for adjusting 80 the slide to different positions, and a plurality of spaced apart centers extending one over the other from the slide, said guide block at one side of the slide carrying a measuring scale for directing the extent of 85 adjustment of the slide, and said slide being provided with an indicating mark for use in relation to said scale, substantially 90 as and for the purposes described.

2. A drill holder comprising a supporting 95 bar provided at one end with a trough to receive the end of a drill, a bracket adjustably mounted adjacent the other end of the bar, a vertically positioned guide block located adjacent the bracket, means to adjust 100 said block toward or away from the bracket, a slide mounted for vertical adjustment on the guide block, means for adjusting the slide to different positions, and a plurality of spaced apart centers on the slide positioned one over the other, said guide block being equipped with a measuring scale and said slide with a direction mark for use in relation to said scale, substantially as and for the purposes 105 described.

3. A drill holder comprising a supporting bar formed at one end with a drill receiving trough, a bracket adjustably mounted adjacent the other end of the bar, and means mounted on the bracket for adjustment toward or away from the bracket and for vertical adjustment, said means being adapted to engage with the end of the drill shank, and including a plurality of spaced apart centers for engagement with different sizes 115 of drills, substantially as described.

4. A drill holder comprising a bar provided at one end with a drill receiving trough, a bracket adjustably mounted on the bar adjacent its opposite end, a guide block mounted on the bracket for adjustment toward or away from the bracket, a slide mounted on the block, means for adjusting the slide vertically to different positions, and a plurality of centers located in spaced 125 130

apart relation one over the other and extending from the slide toward said trough, substantially as described.

5. A drill holder comprising a bar formed at one end with a drill receiving trough, a slide carried by the bar adjacent its opposite end and having means of mounting on the bar whereby said slide may be adjusted to-

ward or away from the trough and also vertically to different positions, and a plurality of equally spaced centers projecting from the slide toward said trough, substantially as described.

In testimony whereof I affix my signature.

ARTHUR WILLIAMS.
